Application May 8, 1935, Serial No. 20,380
In Germany August 4, 1934

3 Claims. (Cl. 311—33)

This invention relates to a table with rotatable middle part of the top. The rotatable middle part of the table serves for carrying food-dishes, bottles and other vessels, which by the turning 5 middle part are to be brought to persons sitting at the table.

For this purpose a device is provided by which a person sitting at the table can move with his foot the rotatable middle part in both directions. 10 A brake is likewise provided for stopping the middle part and holding it still, this brake being likewise actuated by the foot of a person sitting at the table and enables the rotatable part to be braked gradually and without shocks so that the 15 viands are not spilled or tall articles, such as bottles, turned over by too sudden braking.

An embodiment of the invention is illustrated by way of example in the accompanying drawings in which:—

20 Fig. 1 shows the table in side elevation with the lower portion in section on line I—I of Fig. 2, the spring for applying the brake being omitted to enable the other parts to be more clearly seen.

Fig. 2 is a horizontal section on line II—II of Fig. 1.

Fig. 3 shows the middle lower portion of Fig. 1 on a larger scale.

Fig. 4 is a vertical section on line IV—IV of Fig. 2, the pedal lever being omitted for the sake of clearness.

The table illustrated in the drawings is designed for four persons and consists in known manner of a rigid table top 2 (Fig. 4) resting on a frame 3 and four legs 4 fixed on the frame 3 and interconnected at a short distance above the floor by a cross-like stay 5. The frame 3 is closed at the bottom by a bottom plate 6. The table top 2 has a circular aperture in the middle in which 35 a circular rotatable plate 7 is arranged which is rigidly connected with and carried by a vertical axle 8. This axle 8 is journaled near its upper end in a collar bearing 9 fixed on the bottom plate 6 and at its lower end in a step bearing 10 fixed on the cross stay 5. The bearings 9 and 10 may, as shown, be constructed as journal bearings or in known manner as roller bearings. Moreover, the collar bearing may be arranged on the cross stay 5 and the step bearing 40 on the bottom plate 6 without departing from the scope of the invention.

A driving disc 11 serves for rotating the plate 7. This disc is arranged on the axle 8 above the cross stay 5 and is connected to the axle by a 45 kind of flange 12. The disc 11 is rotated by

the foot of a person sitting at the table and can evidently be easily actuated by any person and from any place and in either direction of rotation. The disc 11 may be made of any material and is preferably provided with a covering which 5 affords a good hold for the feet. By turning this disc 11 the axle 8 and the middle plate 7 with the dishes, bottles and the like resting thereon are also rotated at the same time. It must be possible for any of the four persons sitting at the 10 table to brake the rotary plate 7 gently and free from shock and to stop the same in any desired position. For this purpose a friction brake is arranged on each of the four arms of the cross stay 5, as shown in Figs. 2 and 3. Each brake 15 comprises a pedal 13 arranged under the arm of the cross stay 5 and having an upwardly bent end 14 with a pivot pin 16 carried in a hinge 15 arranged on the upper surface of the arm of the cross stay 5. The other end of this pedal 13 projects laterally under the arm of the cross stay 20 and carries a covering 17 of wood or the like with a brake block 18. The covering 17 serves as foot rest and can therefore be bevelled (see Figs. 1 and 3). When the pedal 13 is swung upwards 25 about the pin 16, the upper side of the brake block 18 bears against the under side of the driving disc 11 and thus prevents the rotary plate 7 from turning. By depressing the pedal 13 the brake 30 is disengaged. The brake block 18 is pressed against the disc 11 by a spring 31 hereinafter described. In many instances it is sufficient to arrange a brake block 18 only on one or two instead of on all the pedals 13.

For rotating the disc 11 it is necessary to disengage all four brakes at the same time. For this purpose the following device is provided:—

A disc 33 is fixed, for example by countersunk screws, in the middle on the underside of the cross stay 5, this disc 33 having a downwardly projecting screw pin 20. A capstan wheel 19, which has as many arms as there are brakes, is oscillatable about this pin 20 and secured theron by a nut 21 and washer 22. Each of the arms of 45 the capstan wheel 19 has at its free end a downwardly bent lug 23 with a slot 24 open at its lower end. Each of the pedals 13 has on its rear end 45 a lug 25 terminating in a pin 26 directed towards the middle of the table and each of these 50 pins engages in one of the slots 24 in the lugs 23 on the capstan wheel 19. If one of the pedals 13 is swung downwards by treading on its covering 17, its brake block 18 moves away from the underside of the disc 11 and its lug 25 with its pin 26 55

is moved in clockwise direction (Figs. 1 and 3). As however, this pin 26 engages one of the slots 24 in the lugs 23 on the capstan wheel 19, it rotates this capstan wheel a short distance in 5 clockwise direction (Fig. 2). However, the lugs 23 on the other three arms of the capstan wheel 19 shift the pins 26 of the other three pedals and thus move the other brake blocks 18 away from the driving disc 11. Therefore, by depressing any 10 one of the pedals all four brakes are disengaged and inversely, when pressure is removed from a depressed pedal, all four brakes are applied at the same time. A block 27 with a short pin 28 is arranged laterally of one of the arms of the cross 15 stay 5. The side of the arm of the capstan wheel 19 opposite this block 27 is provided with a disc 29 and a short pin 30. Between the block 27 and the disc 29 a cylindrical pressure spring 31 is arranged, with its two ends slipped on to the pins 20 28 and 30 so that this spring is supported on the parts 27 and 29. This spring tends to turn the capstan wheel 19 in anti-clockwise direction (Fig. 2) and to thus press the brake blocks 18 against the under side of the disc 11, whereas the depression of one of the pedals 13 and consequently 25 the disengagement of the brake takes place against the action of the spring 31. If the foot is removed from a depressed pedal, the brake blocks are pressed against the disc 11 by the 30 spring 31 so that this disc is braked and stopped. A collar or adjusting ring 32 mounted on the axle 8 and bearing against the under side of the collar bearing 9 prevents the brake blocks from lifting the disc 11 with the rotary plate 7 of the table top. According to whether the foot is removed 35 slowly or quickly from the depressed pedal, the pressure of the brake blocks in the disc and therefore the braking effect increases slowly or quickly so that it is possible to stop the rotary plate 7 without shock.

40 A solid disc may be provided instead of the capstan wheel 19, this disc having a downwardly bent flange or a plurality of slotted lugs corresponding to the number of brake pedals and a disc or a block on its upper surface against which the spring 31 bears, instead of the disc 29 on the capstan wheel.

I claim:—

45 1. A table with a circular top and several legs interconnected by a cross stay, comprising in combination a rotary plate arranged in the middle of

the table top, a vertical axle carrying said rotary plate, a horizontal driving disc mounted on the lower end of said axle and adapted to be rotated by the foot of a person sitting at the table to rotate said rotary plate, a pedal pivotally mounted on 5 said cross-stay, a brake block connected with said pedal and adapted to bear against the under side of said driving disc, and a spring adapted to swing said pedal to press said block against said disc.

10 2. A table with a circular top and several legs interconnected by a cross stay, comprising in combination a rotary plate arranged in the middle of the table top, a vertical axle carrying said rotary plate, a horizontal driving disc mounted on the 15 lower end of said axle and adapted to be rotated by the foot of a person sitting at the table to rotate said rotary plate, pedals pivotally mounted on said cross-stay, brake blocks carried by said 20 pedals adapted to be pressed against the under side of said driving disc, a horizontal rotary disc situated below said cross stay and having slots in its periphery, pins arranged one on each of said 25 pedals and engaging one in each of said slots, a spring bearing at one end against said cross stay and at the other end against said rotary disc, said spring adapted to press said brake blocks against the under side of the driving disc through the intermediary of said rotary disc and said pins.

30 3. A table with a circular top and several legs interconnected by a cross stay, comprising in combination a rotary plate arranged in the middle of the table top, a vertical axle carrying said rotary plate, a horizontal driving disc mounted on the lower end of said axle and adapted to be rotated 35 by the foot of a person sitting at the table to rotate said rotary plate, pedals pivotally mounted on said cross-stay, brake blocks carried by said 40 pedals adapted to be pressed against the under side of said driving disc, a horizontal capstan wheel with as many arms as there are brake blocks situated below said cross stay and having 45 slots one in the end of each arm, pins arranged one on each of said pedals and engaging one in each of said slots, a spring bearing at one end against said cross stay and at the other end against said capstan wheel, said spring adapted to press said brake blocks against the under side of the driving disc through the intermediary of 50 said capstan wheel and said pins.

HEINRICH SIEWERS.
